MANUFACTURE OF CERAMIC ARTICLES

Major E. Gates, Crystal Lakes, Ill.

Application August 27, 1946, Serial No. 693,235

10 Claims. (Cl. 25—156)

1

This invention relates to the manufacture of ceramic articles, such as brick, block, etc. Among other objects the invention aims to improve the quality and reduce the cost of manufacture of ceramic products.

The nature of the invention may be readily understood by reference to one illustrative method of manufacture and one illustrative apparatus for practicing the method, described in the following specification and illustrated in the accompanying drawings.

In said drawings:

Fig. 1 is a fragmentary plan section through a tunnel kiln, and showing the ware therein in plan view;

Fig. 2 is a diagrammatic view on a smaller scale of the kiln and ware as arranged in Fig. 1;

Figs. 3 and 4 are similar diagrams showing a different arrangement of ware;

Fig. 5 is a transverse section of a tunnel kiln showing the ware in elevation; and

Fig. 6 is a fragmentary perspective view of a bench or stack of ware.

The illustrative method is shown applied to the making of brick, but it will be understood that it is applicable to other articles which are stacked or associated for processing in rather close relationship. Processing, which includes oxidation and subsequent burning or firing, is carried on in a tunnel kiln 10 which may be either of the circular or straight type. The traveling floor 11 embodies a refractory top 12 whose margins 13 travel in grooves 14 in the kiln walls 15, thereby to protect the floor rolling and supporting structure from the heat of the kiln. Continuous circular baffles 16 traveling in a bed of sand 17 assist in protecting this structure from high temperatures.

In the straight type the ware is passed through the kiln on a succession of separate cars or floor sections which are introduced at one end and removed from the other end of the kiln. In the circular type the cars or floor units are connected together to form a continuous circular platform surrounded by the kiln walls except for a small sector where the ware is removed and unburned ware is introduced. Each car carries a bench or stack of ware which is separated by a substantial space (much wider than the passages between the pieces of ware) from the stacks on adjacent cars. In general the ware is arranged so as to provide transverse and longitudinal passages or flues through the bench of such size as to conduct an adequate volume of heating gases. In the case of brick or similar ware it is advanta-

2

geously stacked in checker brick fashion comprising superimposed tiers 18 of spaced rows 19 of brick running alternately transversely and longitudinally of the kiln. This spacing thus provides alternate tiers or series of longitudinal gas flues or passages 20 and transverse flues or passages 21. Even in those circular kilns which have a continuous type of floor or platform (except for expansion joints therein), the circular character of the floor (wherein the circumference of the inner periphery of the floor is less than the outer) makes it necessary to arrange the ware in separate stacks or benches separated by a space. This is because it would be difficult to stack the ware in a continuous stack due to difference in spacing necessitated by the unequal lengths of the inner and outer portions of the kiln floor. The space between benches is as narrow as practicable but it nevertheless provides a substantial passage through which an excessive volume of heating gases can short circuit.

In tunnel kilns whether they be of the straight or discontinuous type, or the circular type, the heat exchanging gases travel counter to the travel of the ware. Thus cool air is drawn in adjacent the exit end of the kiln picking up heat from (and thereby cooling) the burned ware. The gases continue to the firing or burning zone where the temperature reaches that necessary to effect burning of the ware, i. e., 1800° F. to 3000° F. depending on the character of the clay and results desired. These very hot gases then traverse the ware in the oxidation zone of the kiln, i. e., the ware approaching the burning zone. They are gradually reduced in temperature as they approach the entrance end of the kiln, and the pieces of ware are correspondingly increased in temperature from the entrance end of the kiln to the burning zone.

The oxidation zone is of great importance where the clay contains a substantial amount of oxidizable substances and where it matures at relatively low temperatures. In this zone oxidation of impurities and perhaps other chemical changes takes place, preceded by drying out of traces of water. The temperatures range from 700° F. to 1500° F. depending upon the nature of the material to be oxidized. Very often such material as coal or other matter of a vegetable source is found in the clay. It is not uncommon to find very thin strata of vegetable matter or coal in clay beds which cannot by any practicable means be separated from the strata of clay. It is important that this matter be oxidized before the ware is raised to burning temperatures, other-

wise it will have a reducing effect on iron and other materials in the clay with a consequent reduction of the fusing temperature, resulting in ware with a hard glassy center and other imperfections. The premature fusing of the clay is highly objectionable for other reasons since it tends to close the pores in the ware and prevent escape of gases.

Where a substantial amount of oxidizable substances are present in the clay the length of the oxidation zone i. e., the period of oxidation, is preferably quite long to insure that the center of the pieces of ware (which obviously are difficult to heat and relatively inaccessible to oxygen) will be properly oxidized without excessively heating the exterior of the ware. In such cases relatively less of the kiln length can be devoted to burning, and it is therefore of even greater importance (than for purer clays) that the ware be efficiently and uniformly raised to burning temperatures. The temperature gradient, preferably, should be linear, i. e., the temperature should rise at a uniform rate, as the ware approaches the burning zone. This is desirable not only to provide an opportunity for distribution of heat throughout the ware and to secure efficient and complete oxidation, but to avoid the sudden increase in temperature which would otherwise occur as the ware entered the hot burning zone. This would result in excessive burning and vitrification of the ware on the exterior of the stack, and insufficient heating of the interior of the stack, no matter how efficient the distribution of heating gases throughout the benches.

Optimum results, i. e., maximum speed of travel through the kiln and the best quality of product, can be secured only if all portions of the stack of ware be heated uniformly and at the same rate at all points in the oxidation and burning cycles. Uniformity of heating throughout the stack of ware permits effective control of temperatures which has not heretofore been possible. This in turn makes it possible not only to improve the quality of the ware but to increase the production by increasing speed of travel through the kiln. Ware on the outside of the stack will not be damaged because of the difficulty in heating the ware on the interior of the stack. Conversely the ware on the interior of the stack will not be underheated.

Since heating for oxidation and other treatment of the ware on the interior of the benches must be effected almost entirely by convection, i. e., circulation of hot gases, it is therefore of the utmost importance that the hot gases circulate efficiently and uniformly throughout the interior of the stack of ware. This has presented a difficult problem and unsuccessful attempts have been made to solve it. Instead of passing through the stack of ware, the hot gases have heretofore tended to short circuit or take the path of least resistance through spaces around the exterior of the ware. These spaces are unavoidable since the ware cannot be stacked so as to travel too closely to the surface of the walls or roof of the kiln. These surfaces warp, buckle and expand in unpredictable ways under the high temperatures existing in the kiln so that even if originally built to very close tolerances, they cannot be depended on to retain their original positions. Moreover the ware itself may expand at certain points in the cycle to reduce the initial clearance. Hence it is the practice to allow a space of about 4" between the exterior of the stack and the kiln surfaces, to avoid possibility of a wreck of the ware

in the kiln. A wreck is obviously serious since it requires shutting down of the kiln and a long delay while the kiln and ware cools sufficiently to permit workmen to remove the ware. Much of the ware will be damaged and defectively burned.

The result is that the great majority of the gases travel on the outside of the stack of ware where only the exterior pieces of ware are heated. Some gases travel longitudinally through the interior of the stack of ware but since these are isolated from the exterior gases, they soon lose their heat and soon serve no useful purpose. Travel of gases transversely, i. e., from side to side of the stack has been negligible. Various attempts in special kiln design and by the use of fans have been made to improve the transverse flow of gases through the stack of ware but these have been unsuccessful for various reasons, among those being the short circuiting of the gases through the spaces between adjacent benches of ware. Fans are not effective in producing efficient transverse flow at all points in the kiln.

In the illustrative method the ware is so arranged as to produce pressure differences on opposite points in the stack or bench, thereby causing hot gases to travel through the transverse flues in the stack and to mingle repeatedly not only with the gases traveling through the longitudinal flues but those which travel through the spaces along the exterior of the stacks. This results in an efficient heat exchange which raises the temperature of the longitudinally and transversely traveling streams of gases and correspondingly reduces the temperature of the hot gases traveling through the spaces around the exterior of the stacks. Thus the ware on the interior of the stack is efficiently and uniformly heated throughout and that on the exterior is not overheated.

In the method illustrated transverse flow of heating gases through the interior of the stack is effected by arranging the ware so as repeatedly to change the section of the passages along the sides of the benches of ware in such a way as to produce transverse pressure differentials. Preferably the benches 22 are slightly skewed relative to the direction of travel of the ware (indicated by arrow 23), repeatedly to restrict and enlarge the clearance passages 24 along the sides of the benches. In the illustrative method the passages are sharply restricted at 25 at the outermost corners of the bench. Where, as illustrated in Figs. 1 and 2, the benches are similarly skewed, this results in a sharp enlargement of the passage at 26 at one side of the kiln and a gradual enlargement as at 27 of the passage along the other side. This produces pressure differentials transversely of the benches which cause the heating gases to travel through the transverse passages 21 as well as through the longitudinal passages 20 inside the benches. In this connection it should be remembered that the flow of gases through the kiln is counter to the travel of the ware. The term "transverse" as applied to flow is used in a broad sense to include diagonal or other flow from side to side of the kiln.

The clearance between the outer corners 28 of each bench is sufficient to avoid contact with any bulging kiln walls, but with the present arrangement contact is not nearly so serious as when the benches are generally parallel with the kiln walls and all portions of the sides of the bench are likely to contact with a bulging wall. In the present case even if the outer corners

should contact with a kiln wall, it is not likely to cause a wreck since a displaced brick or other piece of ware will fall into the enlarged space behind the corner where it is much less likely to wedge between the falls and the bench to displace other brick. The result is that if desired, the clearance at the corner 28 may be reduced without increasing the danger of a paralyzing wreck. The narrower the space 25 the greater the pressure differentials created thereby and the greater the transverse circulation through the benches.

The dimensions of the ware in relation to the width of the kiln floor determine to some extent the amount of clearance at the corners 28, particularly if, as is generally the case, the pieces of ware are identical in length. The capacity of the kiln is therefore not reduced over the previous square arrangement of benches because the decreased width of the latter arrangement is not sufficient to accommodate additional ware in the bench with safe clearance. Indeed, as presently explained the capacity of the kiln is greatly increased through the ability to increase the speed of travel through the kiln.

In the illustrative kiln wherein the inner faces of the walls are 55" apart, benches of fire brick (which are 8½" in length), are approximately 43" in width, using only whole fire brick. The length of the bench is also 43". The minimum clearance at the corners 28 may be from 2 to 6" and the maximum clearance at the opposite corner will thus be from 10 to 6". The space between adjacent benches, which as stated above is generally determined by practical considerations, is about 4½". Fire brick are about 2½" in thickness and the spaces between adjacent brick forming the longitudinal and transverse gas passages are about 1½" in width. The dimensions of benches for other differently dimensioned ware will of course vary depending upon the ware itself and the relation between the width of the kiln and the length of a multiple of the length of the individual pieces of ware which can be accommodated in the kiln. Flues between rows of ware vary somewhat as the mass of the ware so as to carry enough heat in the volume of gases passing through the flues, to secure the necessary treatment of the ware.

As illustrated in the arrangement shown in Figs. 1 and 2, gases traveling through transverse passages 21 issue in the diverging longitudinal passage 27 through which they reach the discharge end 29 of such passage. A major part of these gases then travel across the kiln through the gap 30 between adjacent benches. As the transversely flowing gases respectively reach each of the spaces 24 at the sides of each bench, they intermingle with and pick up heat from and correspondingly reduce the temperature of the hot gases which short circuit along the sides of the kiln through the spaces 24. Over-heating of the exterior of the benches is therefore prevented. In the successive gaps 30 the transversely traveling gases also contact with the streams of gases issuing from the longitudinal passages 20 into the space 30 providing an opportunity for heat exchange so that all gases entering the next bench have substantially the same temperature. It is no longer possible for the longitudinally traveling gases to cool to a point where they are ineffective.

Cross travel between the benches is caused of course by the pressure differential existing between the outlets 29 and the inlet 31 of the con-

verging passage 32 on the opposite side of the next bench. Between passages 32 and 27 of the same bench there is a further pressure drop which causes most of the gases to pass through the transverse passages 21 of that bench, issuing in the space 27. This cycle is repeated for each bench, and in the side passages 24 and cross passages 30 at the end of each bench there is the above described heat exchange with the short circuiting gases and the longitudinally traveling gases respectively, thereby equalizing the heating effect of all the gases.

Thus, while a substantial volume of gases still travels through the side passages 24 and through the restricted throats 25, their over-heating effect has been eliminated. Moreover, the volume so traveling is not as great as what would travel if the passages were uniform in section, because the energy of the gases is dissipated to a greater extent in the present arrangement. This energy can be further dissipated by making the kiln walls rough, as by slightly skewing the brick of the kiln walls so that their inner corners are offset as at 32' (see Fig. 1).

The passages 27 advantageously increase in section so as at least to equal the progressive aggregate of the sections of the transverse passages 21 opening into the diverging passage 27. There is then no tendency to convert the velocity head of the gases into pressure head and thereby reduce the pressure differential on the transverse passages 21.

Where gas velocities do not exceed 5 to 7 miles per hour, the laws governing flow are not the same as for more rapid flow. Low flow is sometimes termed viscous flow as distinguished from turbulent flow by which gases traveling at higher velocity is characterized. For viscous flow the pressure head or differential required to produce flow varies directly as the velocity and not as the square of the velocity for turbulent flow. At low velocities it is thus possible to have a greater flow in proportion to pressure differential than at higher velocities. At some restricted points, such as 25, along the sides of the kiln, the velocities in ordinary kiln operation are probably in excess of 5 to 7 miles per hour, but transversely through the passages 21 the flow probably may be characterized as low flow and respond to the laws governing low flow.

Other arrangements of ware than that illustrated in Fig. 1 will produce similar results. For example, in Fig. 3 the benches are skewed in alternate directions. In such case transverse flow from one bench to the next is indicated by the arrow 33. There is little or no cross flow through the spaces 34 between the benches since there is no pressure drop or differential across these passages. Hence there is no opportunity for efficient heat exchange with the longitudinally traveling gases. Furthermore this arrangement is more wasteful of kiln space. Better results could be obtained by more complex benches, i. e. of non-rectangular sections such as illustrated in Fig. 4 where each row of ware is laterally offset from the next. This offsetting could also be varied considerably as by simulating the arrangement in Fig. 1. All of these special arrangements require vastly more skill in setting and therefore greatly increase costs without compensating advantages.

A further advantage of the rectangular or square bench for brick and similar ware, is that the bench can be handled by mechanical brick loaders now in use, thus avoiding the labor of

stacking one brick at a time. The brick can be stacked in bench form at the brick press, carried through the dryer, and then mechanically transferred as a unit to the kiln floor. The same result can be accomplished without the brick loader if the kiln be built with removable car or floor sections each of a size to hold one bench. The bench is then built at the brick press on a floor section which is carried through the dryer and then transferred bodily with the bench to the kiln to replace another section removed from the kiln with its burned brick.

Summarizing: substantial improvement in quality and reduction in cost of production can be effected by the aforesaid method because it permits efficient temperature control and increase in speed of travel through the kiln. The temperature gradient, being substantially linear, brings the ware uniformly throughout the bench to desired temperatures in a minimum time. Heretofore ware on the interior of the bench was insufficiently heated to complete oxidation at the proper stage, with the result that the gases developed on the interior at a later stage in the cycle under higher temperatures had difficulty in escaping because of reduction in porosity of the surface of the ware under such higher temperatures, thereby bloating the ware. Ware with black centers also is chargeable to the action of the high temperatures on incompletely oxidized interiors of the ware. To overcome this speed of travel through the kiln was reduced but with the risk of over-burning the ware on the exterior of the bench. Uniform heating throughout the bench according to the present invention therefore not only makes it possible to increase production by increasing speed, but at the same time to produce more perfect ware.

Another advantageous consequence of the foregoing method is a reduction of the undesirable results of the "stack" action of gases in the kiln. The very great difference in temperatures between the gases on the inside of the kiln and the atmosphere on the outside causes the gases to rise in the kiln through displacement by cold air entering the bottom of the kiln. This is serious at the entrance end of the kiln since the current of air along the bottom is counter to the current of heating gases and thus tends to neutralize or reduce the current along the lower portion of the kiln and correspondingly increase it at the top. The arrangement of ware in the kiln according to the aforesaid method very substantially increases the resistance to travel of gases entering along the bottom of the kiln and correspondingly resists increased travel in the opposite direction of the hot gases at the top of the kiln. Thus the tendency to non-uniformity in heating between the top and the bottom of the kiln due to the stack effect, is minimized.

Obviously the invention is not limited to the details of the illustrative method or the apparatus for performing it since these may be variously modified. Moreover, it is not indispensable that all features of the invention be used conjointly since various features may be used to advantage in different combinations and sub-combinations.

Having described my invention, I claim:

1. The method of treating ceramic ware in a tunnel kiln which comprises placing successive generally rectangular stacks of ware on

the kiln floor spaced from the kiln walls with the stacks skewed to place one pair of diagonally opposite corners of each stack substantially closer to the kiln walls than the other corners, moving the kiln floor to carry successive stacks through the kiln, arranging the ware in each stack with longitudinally and transversely extending passages to carry heating gases between the pieces of ware, causing heating gases to pass longitudinally through the kiln through the spaces between the benches and the kiln walls and counter to the direction of travel of the ware, locating said diagonally opposite corners relatively closely to the kiln walls to create pressure differentials at opposite ends of said transverse passages to cause a substantial portion of the heating gases to pass through the transverse passages in each stack.

2. The method of treating ceramic ware in a tunnel kiln which comprises arranging the ware in stacks on the kiln floor to provide longitudinally and transversely extending gas flues through each stack between the pieces of ware and also cross passages between successive stacks, spacing the sides of the stacks from the kiln walls to provide clearance spaces for the travel of hot gases, moving the kiln floor to carry the stacks through the kiln, causing hot gases to travel through said clearance spaces and longitudinal flues, and causing streams of hot gases to pass from a clearance space on one side of a stack through said transverse flues to the clearance space on the opposite side of said stack and there to mingle with and exchange heat with the hot gases in the latter clearance space, and then causing a portion of the mingled hot gases to return through the cross passage at the end of the stack to the first mentioned clearance space and in so returning to mingle and exchange heat with the gases issuing from the longitudinal flues at each of the stack, and repeating said flow of gases for each successive stack.

3. The method of treating ware in a tunnel kiln which comprises building a stack of ware in the kiln with the side walls of the stack non-uniformly spaced from the kiln walls to provide gas flow spaces of varying section between the ware and the sides of the kiln, arranging the ware so as to provide flues for gases extending from one side of the kiln to the other, moving the stack of ware through the kiln, and causing hot gases to pass longitudinally through said spaces of varying section and thereby to create pressure differentials at opposite ends of said flues, said pressure differentials causing a substantial part of said gases to travel through said flues from one side of the kiln to the other.

4. The method of treating ware in a tunnel kiln which comprises stacking the ware in the kiln to provide flues for hot gases extending both longitudinally through the stack of ware and from side to side of the stack of ware, spacing the sides of the stack of ware from the kiln walls to provide clearance spaces for the travel of hot gases, moving the stack of ware through the kiln, causing hot gases to pass longitudinally through the kiln through said spaces and also through the longitudinal flues in the stack of ware, creating pressure differentials at opposite ends of the cross flues to cause hot gases to travel back and forth from side to side of the kiln through the cross flues in the ware to the other side, and causing said gases to mingle with the hot gases travel-

ing along the sides of the stack of ware and also with the gases traveling through the longitudinal flues thereby to distribute heat uniformly throughout the stack of ware.

5. The method of treating ware in a tunnel kiln which comprises placing pieces of ware in stacks on the kiln floor with the faces of the stacks of ware of varying distances from the kiln walls to vary the area of the spaces between the ware and the sides of the kiln thereby to create pressure differentials between opposite sides of the stack, moving the kiln floor to carry the stacks of ware through the kiln, and causing hot gases to pass longitudinally through the kiln, said pressure differentials causing a substantial part of the gases to travel transversely through the stack of ware.

6. The method of treating ware in a tunnel kiln with a traveling floor which comprises placing pieces of ware in stacks on the kiln floor with passages between the ware in the stacks transversely of the kiln, arranging the stacks of ware on the kiln floor with the clearance between the side faces of the stacks and the kiln wall repeatedly varying in section to create pressure differentials between opposite sides of the stack, and causing hot gases to pass longitudinally through said spaces of varying section, said pressure differentials causing a substantial part of the gases to travel back and forth from side to side of successive stacks through said passages.

7. The method of treating ceramic ware in a tunnel kiln which comprises placing benches of ware on the kiln floor with transversely extending gas passages through the benches, arranging successive benches on the kiln floor with the side faces of the benches longitudinally inclined relative to the kiln walls to form restrictions in the spaces between the sides of the benches and the kiln walls so as to repeatedly to restrict the clearance between each kiln wall and the face of said benches, moving the kiln floor to carry the benches through the kiln, causing hot gases to pass longitudinally through said spaces, the restrictions on opposite sides of each bench being displaced longitudinally thereby to create pressure differentials between opposite sides of the bench to cause gases to travel through said transverse passages.

8. The method of oxidizing ceramic ware in a tunnel kiln prior to burning which comprises placing spaced benches of ware on the kiln floor with longitudinally and transversely extending passages between the pieces of ware in the bench, arranging successive benches on the kiln floor with the side faces of the benches longitudinally inclined relative to the kiln walls to form restrictions in the spaces between the sides of the bench and the kiln walls so as repeatedly to restrict the clearance between each kiln wall and the face of said benches, moving the kiln floor to carry the benches through the kiln, causing hot oxidizing gases to pass longitudinally through said spaces, said restrictions on the opposite sides of each bench being offset longitudinally of the kiln thereby to create pressure differentials at opposite ends of the said transverse passages there-

by to cause said hot gases to flow through said transverse passages, said restrictions also causing said gases after issuing from said transverse passages to return to the opposite side of the kiln through the spaces between said benches, thereby effecting a heat exchange between said gases and those issuing from the longitudinal passages in said benches.

9. The method of treating ceramic ware in a tunnel kiln which comprises placing spaced benches of ware on the kiln floor spaced from the kiln walls with longitudinally and transversely extending passages between the pieces of ware in the benches, skewing said benches on the kiln floor to place diagonally opposite corners of the benches closer to the kiln walls than the other corners thereby to restrict the spaces between the bench and each kiln wall, causing hot gases to pass longitudinally through the kiln through the spaces between the benches and the kiln walls, and moving the kiln floor to carry the benches of ware through the kiln in a direction counter to the flow of hot gases through said kiln.

10. The method of oxidizing ceramic ware in a tunnel kiln prior to burning which comprises placing spaced benches of ware on the kiln floor spaced from the kiln walls and with longitudinally and transversely extending passages between the pieces of ware in each bench, spacing the side walls of the benches relatively to the kiln walls repeatedly to restrict and then to enlarge the spaces between the kiln walls and the benches, moving the kiln floor to carry the benches through the kiln, causing hot oxidizing gases to pass longitudinally through the spaces between the bench and kiln walls, the restrictions in said spaces on opposite sides of each bench being offset longitudinally of the kiln to create pressure differentials at opposite ends of the said transverse passages thereby to cause said hot gases to travel back and forth across said kiln through said transverse passages and to exchange heat with the hot gases passing through the passages between the kiln wall and the benches, said restrictions also causing said transversely traveling gases after issuing from a transverse passage to return to the opposite side of the kiln through spaces between said benches, thereby effecting a heat exchange between said gases and those issuing from the longitudinal passages in said benches, whereby heat is uniformly distributed throughout the benches.
